CLAIM

The ornamental design for roofing material display, as shown and described.

DESCRIPTION

FIG. 1 is a front elevational view of a first embodiment of a roofing material display showing my new design;

FIG. 2 is a top plan view thereof, the bottom plan view being a mirror image; and

FIG. 3 is a right side elevational view thereof, the left side elevational view being a mirror image.

FIG. 4 is a front elevational view of a second embodiment of a roofing material display showing my new design;

FIG. 5 is a top plan view thereof, the bottom plan view being a mirror image; and

FIG. 6 is a right side elevational view thereof, the left side elevational view being a mirror image.

FIG. 7 is a front elevational view of a third exemplary embodiment of a roofing material display showing my new design;

FIG. 8 is a top plan view thereof, the bottom plan view being a mirror image; and

FIG. 9 is a right side elevational view thereof, the left side elevational view being a mirror image.

FIG. 10 is a front elevational view of a fourth exemplary embodiment of a roofing material display showing my new design;

FIG. 11 is a top plan view thereof, the bottom plan view being a mirror image; and

FIG. 12 is a right side elevational view thereof, the left side elevational view being a mirror image.

FIG. 13 is a front elevational view of a fifth exemplary embodiment of a roofing material display showing my new design;

FIG. 14 is a top plan view thereof, the bottom plan view being a mirror image; and,

FIG. 15 is a right side elevational view thereof, the left side elevational view being a mirror image.

The broken line showing of a detail in FIGS. 1, 4, 7, 10 and 13 is included for the purpose of showing environmental portions of the roofing material display and forms no part of the claimed design.

The rear elevational view of each of the embodiments is flat and devoid of surface ornamentation.
